(57) **CLAIM**

We claim the ornamental design for a flow cell cartridge, as shown and described.

DESCRIPTION

FIG. 1 is a rear top perspective view of a flow cell cartridge comprising our new design;

FIG. 2 is a top plan view of the design in FIG. 1;

FIG. 3 is a bottom plan of the design of FIG. 1;

FIG. 4 is a right side elevational view of the design of FIG. 1;

FIG. 5 is a left side elevational view of the design of FIG. 1;

FIG. 6 is a front elevational view of the design of FIG. 1;

FIG. 7 is an enlarged rear elevational view of the design of FIG. 1;

FIG. 8 is a rear top perspective view of an alternate embodiment of the design shown in FIG. 1;

FIG. 9 is a top plan view of the design in FIG. 8;

FIG. 10 is a bottom plan view of the design of FIG. 8;

FIG. 11 is a right side elevational view of the design of FIG. 8;

FIG. 12 is a left side elevational view of the design of FIG. 8;

FIG. 13 is a front elevational view of the design of FIG. 8;

FIG. 14 is an enlarged rear elevational view of the design of FIG. 8;

FIG. 15 is a bottom plan view of an alternate embodiment of the design shown in FIG. 8; and,

FIG. 16 is an enlarged rear elevational view of the design of FIG. 15.

The top perspective, top plan, right, left, and front elevational views for the embodiment shown in FIG. 15 are identical to FIGS. 8-9, and 11-13. The broken lines shown in the drawings illustrate portions of the flow cell cartridge that form no part of the claimed design.
